UNITED STATES PATENT OFFICE.

WALTER H. DANIELS, OF SAVANNAH, GEORGIA.

SEPARATING TRAP.

Application filed August 21, 1922. Serial No. 583,286.

To all whom it may concern:

Be it known that I, WALTER H. DANIELS, a citizen of the United States, residing at Savannah, in the county of Chatham and State of Georgia, have invented a new and useful Separating Trap, of which the following is a specification.

The device forming the subject matter of this application is a trap adapted to permit the passage of air and steam but intended to close against the passage of water, the structure being of peculiar utility in connection with a thermostatic air valve for the elimination of air from a steam line.

The invention aims to provide novel means whereby the outlet may be closed rapidly as the water rises, rather than against the rise of water.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in vertical longitudinal section, a device constructed in accordance with the invention, parts appearing in elevation; Figure 2 is a transverse section wherein parts appear in elevation; Figure 3 is a fragmental horizontal section.

In carrying out the invention, there is provided a tank 1 which may be variously constructed. The tank may embody a base 2 and a top 3 secured at 4 to the base. An inlet 5 is formed in the base 2, and the top 3 has an outlet 6. The part 3 is provided with a depending annular flange 7 wherein a tubular seat 8 is held removably, by threading or otherwise, the seat forming part of the outlet 6.

A support or post 9 is mounted on the base 2. A clamp 10 is pivoted at 11 to the support 9 and is held by a securing element 12 on the intermediate portion of a lever 13 carrying a float 14 located within the tank 1. The inner end of the lever 13 is offset downwardly, as shown at 15.

Standards 16 are erected on the base 2. The standards 16 are cut away at their upper ends to define transverse shoulders 17 and a thinned neck 18, in each standard. Upwardly extended guides 19 are disposed on opposite sides of the neck 18 of each standard 16 and are held thereon by securing elements 20, the lower ends of the guides being received by the shoulders 17. The upper ends of the guides 19 of each standard 16 are held together in any suitable way, for instance by spacers 21 and securing elements 50.

The device includes a valve, denoted generally by the numeral 22 and including a stem 23 provided at its lower end with a fork 24, the arms of the fork having longitudinal slots 25. The stem 23 of the valve 22 carries a head 26 whereon a disk 27 is held by a washer 28 and a nut 29 or in any other suitable way, the disk 27 being made of fibre or any other suitable material not subject to deterioration. The disk 27 is the part of the valve which cooperates immediately with the seat 8 when the valve moves upwardly.

The numeral 30 marks a lazy tongs received at its outer edges between the guides 19 slidably. The end 15 of the lever 13 is mounted pivotally in the lower end of the lazy tongs 30. The fork 24 of the valve stem 23 straddles the upper end of the lazy tongs 30. The uppermost pivot element 31 of the lazy tongs forms a connection between the lazy tongs and the fork 24. An intermediate pivot element 32 of the lazy tongs is received slidably in the slots 25 of the fork 24 and, thus, the valve 22 is maintained in the position shown in Figure 2 of the drawings.

When water rises in the tank 1, the lever 13 is tilted, responsive to the action of the float. The lowermost members of the lazy tongs 30 rest on the upper ends of the necks 18 of the standards 16 and are fulcrumed thereon. Consequently when the lever 13 tilts responsive to the float 14, as the water rises in the tank, the lazy tongs 30 will be elongated and the valve 22 will be closed with respect to the seat 8. Through the instrumentality of the lazy tongs 30, the movement of the lever 13 is multiplied greatly and the valve 22 will move with correspondingly increased speed toward and away from the seat 8. The valve 22 may be located at considerable distance from the

seat 8, so as to afford a good clearance at the outlet port 6, a small movement of the lever 13 bringing about a greatly increased movement of the valve.

5. What is claimed is:—

1. A device of the class described comprising a tank having a seat; horizontally spaced vertical guides in the tank; a lazy tongs directed throughout its length by the 10 guides and supported by the guides; a float-operated lever fulcrumed in the tank and connected with the lazy tongs; and a valve carried by the lazy tongs and coacting with the seat.

15. 2. A device of the class described comprising a tank; guides in the tank; a lazy tongs slidably received in the guides; means for supporting the lazy tongs at its lower end; a float-operated lever in the tank and connected to the lazy tongs; and a valve car-

ried by the lazy tongs, the tank having a seat wherewith the valve coacts.

3. A device of the class described comprising a tank; a seat carried by the tank; a float-actuated lever in the tank; a lazy 25 tongs assembled with the lever; means for supporting the lazy tongs; means for guiding the lazy tongs; and a valve cooperating with the seat; the lazy tongs embodying pivot elements one of which supports the 30 valve, the other of which constitutes a guide whereon the valve is received slidably.

In testimony that I claim the foregoing as my own, I have hereto affixed my signature in the presence of two witnesses.

WALTER H. DANIELS.
